UNITED STATES PATENT OFFICE

2,589,001

SPRING CLIP DEVICE

Joseph Villano, Brooklyn, N. Y.

Application June 8, 1948, Serial No. 31,795

2 Claims. (Cl. 24—255)

1

My invention relates to spring clip devices and aims to provide certain improvements therein. More particularly it relates to a spring clip device which is adapted to be anchored to a wall or the like and having an ornamental cap between which and one end of the clip an article such as a curtain tie-back, a hat or the like, is adapted to be securely held.

Among the objects of the invention are to provide a spring clip device which is simple in construction, easy to apply to a wall, door or other supporting member, which is effective in use and in which the spring serves both as the support for the ornamental cap and for normally holding the ornamental cap in article-securing engagement. A further object is to provide a device of the character set forth wherein the ornamental cap serves as the operating means for releasing an article held by the device.

The foregoing and other objects of my invention not specifically enumerated I accomplish by providing a spring clip device comprising a leaf-spring with means intermediate the ends thereof for detachably securing it to a support, said spring being of a form such that one end thereof supports an ornamental cap and normally holds it in cooperative engagement with the other end of the spring to provide the holding engagement for the article and wherein the application of pressure to the ornamental cap at its spring-supported end in a direction toward the supporting means will operate to release the holding engagement on the held article. The invention will be better understood from the detailed description which follows when considered in connection with the accompanying drawings, wherein:

Figure 1 is a front elevation of a window showing the spring clip devices of my invention employed as curtain tie-back holding means.

Fig. 2 is a section on an enlarged scale taken substantially along the plane of the line 2—2 of Fig. 1.

Fig. 3 is a front elevation of my invention as applied to a hat holding means or the like.

Fig. 4 is a section taken substantially along the plane of the line 4—4 of Fig. 3.

Referring first to Figs. 1 and 2 of the drawings, the spring clip device of my invention comprises a leaf-spring 10, a cap member 11 and securing means 12 for attaching the device to a window frame 13 or the like.

The spring 10 is of substantially flattened V-shape construction providing a pair of arms 14 and 15, the arm 14 having a reversely curved end 16 and the arm 15 adjacent the free end thereof

2

being secured to the rear face of the cap member 11 adjacent one end or periphery thereof by securing means such as tacks 17. The spring is of a shape such that when connected to the cap member in the manner set forth, the opposite end or diametrically opposite peripheral portion of the cap member will frictionally engage the arm 14 inwardly of the end 16 and provide therewith holding means for an article such as a curtain tie-back 18 which engages around the folds of a curtain 19 hung in a conventional manner from a bracket or rod (not shown).

The securing means 12 as herein shown is a wood screw preferably non-rotatively extending through an opening in the spring at substantially the apex of the V but it will be understood that any suitable securing means may be employed for this purpose.

The cap member 11 may be formed of any desirable material and in any ornamental design and, as herein shown, is of a character which will receive the tacks 17 to hold the cap member to the spring. Where the cap member is formed of metal, plastic or other material suitable well known means for securing such material to the spring may be employed.

In view of the relationship of the parts hereinbefore described it will be apparent that normally the unsecured end or peripheral portion of the cap 11 will be held in frictional engagement with the spring arm 14 due to the tension of the spring arm 15. Hence, when pressure is applied to the secured end of the cap in a direction toward the securing means 12 or window frame 13, as indicated by the arrow 20 in Fig. 2, to move the cap member to the dot and dash position, the holding engagement provided between the cap and the spring arm 14 will be released so that the tie-back 18 may be simply and quickly removed from its curtain holding relation.

In the embodiment of my invention shown in Figs. 3 and 4 although the spring 10a is of slightly different shape from that shown in Fig. 2, its securing means 12a and tacks 17a, as well as the relationship of the cap 11a to the spring are all precisely the same as in Fig. 2. By having the arm 14a of the spring relatively long as compared to the arm 15a it will be appreciated that the device may readily serve as a means for holding the brim of a hat 22 or other device wherein the gripping portion is substantially inwardly from the edge of the device.

Although I have shown and described two embodiments of my invention and two specific

applications thereof, it will be appreciated that the cooperating portions of the spring arm 14 and cap 11 may assume a relationship other than that shown, and that other changes in the specific details of construction and arrangement of parts may be resorted to within the range of mechanical skill without departing from the spirit of my invention as claimed.

What I claim is:

1. A spring clip device comprising a leaf-spring having a substantially flattened V-shaped portion with means at substantially the apex of the V-shaped portion for detachably securing the device to a supporting member, a cap attached to one arm of the V-shaped portion and extending across the other arm in overlying relation thereto and normally providing therewith clamping engagement means for holding an article, the cap at its spring-attached end being adapted, upon application of pressure thereto in a direction toward the supporting member, to release the clamping engagement means from its article-holding position.

2. A spring clip device according to claim 1 wherein the cap completely overlies the leaf spring and the means for securing the spring to the supporting member.

JOSEPH VILLANO.
